John Pomfret Sr. INVENTOR

UNITED STATES PATENT OFFICE.

JOHN POMFRET, SR., OF PATERSON, NEW JERSEY.

STEAM BOILER.

Application filed March 19, 1926. Serial No. 95,831.

My invention relates to improvements in steam boilers, in which the heating surface is provided at suitable places with tubes closed on one end and opening into the boiler, 5 and having three or more chambers therein.

The objects of the invention are to afford a greater heating surface and to improve the circulation of water therein, thereby economizing in the use of fuel and decreasing the gathering of sediment in the area of the firebox. In high pressure boilers, the invention may be placed between stay bolts and crown bolts in the firebox, and it may also be used in low pressure boilers having 15 no stay bolts.

I attain these objects by the mechanism illustrated in the accompanying drawing, in which—

Figure 1 is a plan and elevation of the 20 tube,

Figure 2 is a plan and elevation of the diaphragm when separated from the tube,

Figure 3 is a plan and elevation of the tube with the diaphragm inserted therein,

25 Figure 4 is a plan view of the tube in connection with a section of firebox, and

Figure 5 is an elevation of the tube in connection with a section of firebox.

Similar numerals refer to similar parts 30 throughout the several views.

The cylindrical tube (1) is closed and convex at one end. Round the outer edge of the orifice of the tube runs a thread (2), so that the tube may be screwed into a 35 tapped hole in the boiler plate (5) and welded. The diaphragm (3) is inserted into the tube (1). The planes of the diaphragm

three in number and having one edge in common, are equal in size and are pressed into the sides of the tube for the greater part 40 of its length but converge to a point (4) in the center of the closed end, thus forming in the tube three chambers which have separate openings into the boiler and a common sac at the closed end. 45

I claim—

1. In a steam boiler, a cylindrical tube on the heating surface, closed and convex on one end, the other end being open and having a thread cut round its outer edge and 50 screwed into the boiler plate; having therein a diaphragm comprising three or more equal planes with one edge in common and converging at the closed end, forming three or more chambers in the tube which have 55 separate openings into the boiler and a common sac at the closed end, substantially as described.

2. The combination of a steam boiler with a plurality of cylindrical tubes on the heating surface thereof, each tube being closed and convex on one end, the other end having an orifice opening into the boiler and having a thread round its outer edge and screwed into the boiler plate; each tube having there- 60 in a diaphragm comprising three or more planes having one edge in common and converging at the closed end, forming in the tube three or more chambers which have 65 separate openings into the boiler and a common sac at the closed end, substantially as described. 70
